DEFLECTION CONTROLLED TUBE

Kurt Schlesinger, La Grange, Ill., assignor to Motorola, Inc., Chicago, Ill., a corporation of Illinois
Filed Mar. 31, 1958, Ser. No. 725,270
11 Claims. (Cl. 315—22)

This invention relates to a new and improved crossed-field modulation system for use in cathode-ray tubes to modulate and focus a beam and thereby control the intensity of a spot on a viewing screen.

Cathode-ray tubes in present use include an electron gun having a small area or point cathode modulated by an adjacent grid, which together with a first anode converges the beam into a crossover. A lens is provided to image the crossover on a viewing screen so that a spot is formed thereon, and the grid-modulation controls the intensity of the spot.

Some generally recognized standards for a good electron gun are that it should provide high beam current and resolution, good halftone rendition, high modulation sensitivity, and minimum interaction between control voltage and spot size. For many applications, and particularly those in which the control voltage is developed by transistor circuits, it is desirable for the control characteristic to permit modulation with low voltages of the order of 12 volts or less. It has been found that cathode-ray tubes with conventional grid-modulation control cannot meet all of the above general requirements; there has to be a compromise between brightness and resolution.

Accordingly, one object of this invention is to provide a new and improved system for modulating and focusing an electron beam.

Another object of the invention is to provide a cathode-ray tube with a new and improved intensity control system which has high modulation sensitivity at low beam voltages.

Still another object is to provide an improved deflection control using beam interception in which scattered electrons resulting from such interception are collected separately in order to reduce halation on the screen.

A feature of the invention is the provision of a cathode-ray tube with a large area cathode providing a high current beam which is concentrated by a focusing modulator into a small image-defining aperture which presents a stable size and shape with controlled illumination.

Another feature of the invention is the provision of a focusing modulator assembly having electrostatic electrodes generating crossed-fields simultaneously providing strong focusing fields and weak superimposed deflecting fields, thereby permitting intensity control of a high current electron beam with low control voltages.

Another feature of the invention is the provision of a crossed-field modulator including a slotted-cylinder unit providing two electric fields in a cavity; one field being coaxial for focusing an electron beam, and the other being transversal for deflection modulation of the beam.

A further feature of the invention is the provision of a focusing modulator including two separate bifocal field-generator systems arranged in quadrature along the tube axis, with each system having four pole-pieces shaped as rectilinear hyperbolae, and with the first system receiving the modulating signal along its positive focal plane.

A further feature of the invention is the provision of a new and improved deflection modulation system having a beam intercepting anode, and wherein scattered electrons and secondary emission from the interceptor anode are drawn backward to a collector anode which is positively biased.

A still further feature is the provision of a focusing modulator having a post-focuser at its exit end including

2

a concave profile immediately following an intercepting aperture for concentrating the beam in the presence of post-accelerating fields.

The invention is illustrated in the accompanying drawings in which:

5 FIG. 1 shows a cathode-ray tube including a crossed-field modulator in accordance with one embodiment of the invention;

FIG. 2 is a slightly enlarged cross-sectional view of the modulator structure shown in FIG. 1;

10 FIG. 3 shows a printed ceramic construction for the modulator of FIG. 1;

FIG. 4 is a diagram of a control circuit suitable for use in the cathode-ray tube shown in FIG. 1;

15 FIG. 5 is a curve illustrating the control characteristic of the modulator of FIG. 1;

FIG. 6 shows a modification of the crossed-field modulator structure shown in FIG. 1; and

10 FIGS. 7 and 8 show a cathode-ray tube including a focusing modulator in accordance with another embodiment of the invention.

The invention is a modulation system for cathode-ray tubes in which a high current beam of electrons passes through a focusing modulator including adjacent electrode groups, each having a plurality of pole-pieces bounding a common cavity. The pole-pieces generate crossed electric fields in the cavity which simultaneously exert focusing and deflecting action on the beam. In a slotted-cylinder embodiment, the pole-pieces have a semi-cylindrical shape. In another embodiment, the pole-pieces are shaped as rectilinear hyperbolae. In either case, two or more groups of pole-pieces are closely spaced coaxially to form the common cavity in which deflection and focusing take place. The radial distance from the axis 30 of the cavity to the active faces may vary from one group to another. A form of insulating material is provided to locate the pole-pieces in the proper positions, and the pole-pieces may be provided as coatings of conductive material on the form. In the slotted-cylinder embodiment, the focusing action is provided by a field which acts coaxially of the modulator while deflecting action is provided by fields which act transversely and are, therefore, crossed with respect to the focusing field. In the hyperbolic embodiment, simultaneous deflecting and

35 focusing action is obtained with a single pair of electrostatic 4-pole systems arranged in quadrature along the same axis, with only the first system being connected to the modulating signal. In both embodiments, an apertured interceptor anode is positioned at the exit end of the cavity. The beam of electrons passes through the cavity with little loss since it is converged to form a sharp, small crossover right at the interceptor. The deflecting field causes part of the beam to impinge on an edge portion of the interceptor, while the remainder of the beam passes through the aperture and thus varies with the modulating signal. Electrons which are intercepted 40 tend to scatter, and this may cause undesirable halation of the picture background. To prevent this, a collector anode is positioned behind the interceptor to pull the scattered electrons backward. The collector anode may be a separate apertured disc, or may even be one of the groups of pole-pieces if the cavity therethrough is made to have a sufficiently small diameter at its exit end.

45 In FIGS. 1 and 2 there is shown part of a cathode-ray tube having a focusing modulator of the slotted-cylinder type. Electrons are emitted from the large area cathode 10. The electrons are accelerated away from the cathode 10 into the modulator cavity 33 where they are focussed into a crossover. This crossover is placed right in the

50 cavity with little loss since it is converged to form a sharp, small crossover right at the interceptor. The deflecting field causes part of the beam to impinge on an edge portion of the interceptor, while the remainder of the beam passes through the aperture and thus varies with the modulating signal. Electrons which are intercepted tend to scatter, and this may cause undesirable halation of the picture background. To prevent this, a collector anode is positioned behind the interceptor to pull the scattered electrons backward. The collector anode may be a separate apertured disc, or may even be one of the groups of pole-pieces if the cavity therethrough is made to have a sufficiently small diameter at its exit end.

55 In FIGS. 1 and 2 there is shown part of a cathode-ray tube having a focusing modulator of the slotted-cylinder type. Electrons are emitted from the large area cathode 10. The electrons are accelerated away from the cathode 10 into the modulator cavity 33 where they are focussed into a crossover. This crossover is placed right in the 60 spot defining aperture 44 in the interceptor anode 43. The beam is deflected in response to a modulating signal applied to half of the slotted-cylinder so that the por-

tion of the beam passing through aperture 44 is controlled. A positively biased collector plate 51 having an aperture 52 is positioned behind the interceptor with the edge of aperture 52 closely spaced from the intercepting edge bounding aperture 44 in order to pull back scattered electrons which tend to cause halation on the screen.

The beam diverges after passing through the aperture 44, and is re-converged into an image-forming section 20 by the interaction of a concave meniscus 45 at low voltage and the main lens barrel 17 at higher voltage.

Since the interceptor presents a beam of definite shape with varying illumination, the image forming section may be any of several conventional types, such as bi-potential electrostatic, uni-potential electrostatic, magnetic, and others. The image forming section 20 is preferably of large diameter to reduce spherical aberrations. The imaging lens may also include a second anode 18 which is preferably a coating 18 of conductive material on the wall 19 of the tube. This lens section is adjusted to focus the image of the aperture 44 into a well defined spot on the viewing screen 21.

The cathode 10 is provided with a comparatively large emitting surface 26, and since beam current is proportional to cathode area, high beam currents may thereby be provided. The cathode surface 26 is concave to facilitate focusing. The collimating aperture 27 and the prefocusing end-plate 41 provide a field which preconverges the beam prior to its entry into the modulator cavity 33. Relative placement of cathode 10, collimator 12, and end-plate 41 may be chosen such that the collimator bias optimizes at ground potential.

The modulator 13 includes three pairs of pole-pieces having semi-cylindrical opposed faces which form the slotted cavity 33. One form of the supporting structure for the modulator is shown in FIG. 2. The pole-pieces 34-39 inclusive are lined up in recesses provided in the inner faces of the ceramic plates 79 and 80. These plates are clamped against the electrodes by bolts 75 or rivets. The modulator is supported by metallic discs 77 which are assembled on rods 78 made of ceramic, glass, or other insulating material. The inner faces 81 and 82 of the pole-pieces 38 and 39 respectively, and the manner in which they bound the slotted cavity 33, may be seen clearly here.

The poles 34-39 are shown in FIGS. 1 and 2 as half-rings of metal, but may also be constructed by applying coatings of conductive fire paint to an insulating form such as is illustrated in FIG. 3. The pins 132, preferably of "Kovar," extend through the semicylinders 130 and make contact with the inner surfaces 34-39. In either type of construction, the pole-pairs are separated by narrow insulating gaps 40.

The circuit diagram of FIG. 4 illustrates how electric potentials may be applied to the elements of a modulator structure in accordance with FIG. 1. A potential of about 250 volts may be applied to the two end-plates 41 and 51 in parallel. A slightly lower potential is applied to the interceptor 43 and also to the pole-pairs 34-35 and 38-39. A low voltage bias is applied to the central pole-pair 36-37, and the latter pair may even be grounded. A structure of this type provides a non-linear spatial potential distribution which exerts strong focusing action with low spherical aberration, especially if this spatial potential variation is parabolic. By judicious choice of pole-piece length and bias, the focal length of this modulator may be adjusted so as to focus the beam into a sharp crossover right at the spot defining aperture 44 of the interceptor 43.

When opposing pole-pieces are at the same potential, the field formed thereby has circular symmetry. Therefore, the crossover is centered with aperture 44 and most of the beam passes through it. This symmetrical field distribution exists when the arm 100 on potentiometer 102 is at the center position. By applying different po-

tentials to each half of the cylinder, a transverse field is established between the halves. Thus, the beam is deflected slightly from the center of the aperture 44. This is accomplished by moving the arm 100 either above or below the center position. Then when a modulating signal is applied to one-half of the unit, the effect is to shift the position of the beam focus transversely in response to the variations of the signal.

The picture display from a given signal will be a positive or negative image, depending on the off-center position of the focus with respect to aperture 44. Accordingly, the crossed-field modulator tube is capable of handling picture signals of either polarity by reversing the bias across the cavity. Since the beam voltage in the cavity is comparatively slow, the deflecting field can be weak, and efficient modulation can be had at a low signal level of the order of 12 volts and less. A control characteristic for a modulator in accordance with FIG. 1 is shown in FIG. 5 to illustrate the high modulation sensitivity and the positive-negative picture control described above.

The following dimensions for a cathode-ray tube built in accordance with FIGS. 1 and 2 are given by way of illustration and are not intended to limit the scope of the invention in any way:

10	Separation between cathode 10 and grid 12	0.30
15	Separation between grid 12 and prefocuser 41	0.100
20	Separation between poles 34-35, 36-37, 38-39	0.030
25	Transverse spacing between pole-pairs 34 and 35, 36 and 37, and 38 and 39	0.030
30	Diameter of prefocuser aperture 42	0.100
35	Diameter of grid aperture 27	0.150
40	Diameter of collector aperture 52	0.060
45	Diameter of interceptor aperture 44	0.025
50	Diameter of emitting surface 26	0.060
55	Diameter of cathode 10	0.125
60	Diameter of meniscus 45	0.250
65	Radius of meniscus 45	0.125
70	Diameter of cavity 33	0.250
75	Length of pole-pieces 34-35	1/16
80	Length of pole-pieces 36-39	3/16
85	Thickness of end plates 41 and 51	0.010
90	Thickness of disc 43	0.062

The following circuit values are given for the circuit shown in FIG. 4 only by way of illustration:

Resistor 101	kilohms	22
Resistor 102	do	20
Resistor 103	do	39
Resistor 104	do	470
Resistor 105	megohms	2.2
Resistor 107	kilohms maximum	10
Capacitor 108	microfarads	0.05
Capacitor 109	do	0.01
Capacitor 110	do	0.01

Such a cathode-ray tube has been found to have the following characteristics:

Modulation voltage	12 volts and less.
Maximum transconductance	150 microamperes per volt.
Maximum beam current	1000-1200 microamperes.
Highest voltage needed for modulator	250 volts.
Resolution	Better than 400 lines.

In FIG. 6 there is shown a modification of the modulator of FIG. 1 in which the cavity diameter tapers down towards the exit. In the tapered structure shown here, the faces 91 of pole-pair 61-62 at the cavity exit have a diameter which corresponds roughly to that of edge 52 shown in FIG. 2. Pole-pair 61-62 is maintained at a slightly higher potential than the interceptor 71 to pull

back scattered electrons, and thus no separate collecting structure is required.

A cathode-ray tube provided with a focusing modulator in accordance with another embodiment of the invention is shown schematically in FIGS. 7 and 8. It may be seen that in this embodiment the modulator 140 includes two adjacent quadrupoles 138 and 139 on a common axis and forming a common cavity 153. The active faces of the pole-pieces 141-148 are of hyperbolic shape. The pole-pieces are held in position by a common cylinder 149 of insulating material such as lava, as may be seen in FIG. 8. Slots 151 are provided in the cylinder 149 to locate the edges of the pole-pieces. A broad beam of electrons from the large area cathode 10 passes through the composite system, and will converge to a crossover at the exit end of cavity 153 when proper bias is applied to the pole-pieces. An apertured interceptor 43 is placed at the exit of the cavity. A collector anode 51 is interposed between the interceptor 43 and the cavity.

The action of the modulator 140 is somewhat different from that of modulator 13 of FIG. 1, but there is an overall similarity in construction and the beam passing through the cavity is simultaneously focussed and deflected by crossed-fields. Each quadrupole generates two fields in the cavity 153; one exerting a positive focusing action, and the other exerting a negative focusing action. Voltages are applied to each quadrupole in a balanced-to-anode fashion, as shown at X and Y in FIG. 7. As a result, the average beam velocity stays constant throughout the system. Moreover, experience shows that the potential difference and length of the respective electrodes are inversely proportional. If used independently, each quadrupole would tend to produce a line focus. It has been found, however, that by employing only one pair of quadrupoles with the polarities of one rotated 90° with respect to the other, it is possible to obtain an overall positive focusing action, and under certain conditions of bias this system can produce a point focus. The conditions for obtaining point focus can be described by the equation

$$\frac{f_2}{f_1} = 1 - \frac{a}{f_2}$$

where f_1 is the focal length of the first quadrupole 138, f_2 is the focal length of the second quadrupole 139, and a is the distance between them. The system can be biased to pass the beam through the narrow aperture 44, and the focus is then shifted transversely by a modulating signal applied to one of the poles 142 and 144.

The potentials required to provide this simultaneous focusing and deflecting action are applied to the various elements of the modulator by the circuit shown therewith in FIG. 7. The prefocuser 41 and collector 51 are placed at about 200 volts, and the interceptor 43 is placed at a somewhat lower potential to insure that scattered electrons are collected. Opposite pole-pieces within each quadrupole system are placed at the same potential, with the pairs 141-143 and 146-148 being positive with respect to beam voltage, and pairs 142-144 and 145-147 being negative with respect to beam voltage. The pairs of like polarity in groups 138 and 139 are rotated 90° with respect to each other in order to provide the composite crossed-field effect previously described.

The modulating signal is applied from the signal source 155 to pole-piece 144 to initiate deflection modulation. It is important to apply the signal to one of those electrodes in quadrupole system 138 which is negative with respect to beam voltage so that the first quadrupole system receives the signal along its positive focal plane. If this is done, the beam will move in a plane for which the second quadrupole system is divergent, its corresponding pole-pieces being positive with respect to anode voltage, as shown. Under these conditions, the second quadrupole 139 provides additional deflection even though it is not directly connected to the signal source.

It is apparent from the foregoing description that the crossed-field modulation system of the invention provides a high current gun yielding a spot of definite size and shape. This system has a nearly linear modulation characteristic, and it runs on very low signal voltage. Consequently, a tube provided with such a crossed-field modulator may be operated in a television receiver with a low level of video signal, and is especially suited for use with transistorized circuits which provide signals of only 12 volts or less. The modulation of the beam by partial interception has little effect on spot size. Spurious halation by scatter electrons can be eliminated by the provision of a separate collector anode in back of the intercepting anode. A tube having a control system of this type is capable of displaying positive or negative modulation. This offers the practical advantage of handling signals of either polarity without the need for a separate inverting amplifier.

I claim:

1. In a cathode-ray tube including a viewing screen, and an electron source for directing a beam in a predetermined path against the screen, a crossed-field modulation system for controlling the intensity of a viewed spot formed by the beam on the screen, said system including in combination, a beam intercepting anode located between the electron source and the screen and having a spot defining aperture in alignment with the predetermined beam path, a plurality of adjacent electrode groups located between the electron source and said intercepting anode and each including a plurality of electrostatic poles positioned on opposite sides of the predetermined beam path, said poles having transversely curved active faces extending longitudinally and defining a common cavity for passage of the beam, circuit means having a first portion for applying different biasing potentials to said poles to establish a focusing field in said cavity for converging the beam into a crossover at said edge of said intercepting anode, said circuit means having a second portion for applying a modulating signal to certain of said poles for superimposing a transverse deflecting field on said focusing field which is effective to deflect said beam between one extreme condition wherein the beam is directed at said spot defining aperture and another extreme condition wherein substantially the entire beam is directed on said beam intercepting anode about said aperture, whereby the modulating signal is effective to control the portion of the beam passing through said aperture and striking said screen, thereby controlling the intensity of the viewed spot.
2. In a cathode-ray tube having a viewing screen, and an electron source for directing a beam in a predetermined path against the viewing screen, a crossed-field modulation system as defined in claim 1 having at least three adjacent electrode groups each including two opposed poles, said poles having active faces of semi-cylindrical shape forming a slotted cavity, and said first portion of said circuit means applying a lower potential to the intermediate pole-pair than to the other two to provide a non-linear spatial potential distribution exerting strong positive focusing action.
3. In a cathode-ray tube including a viewing screen and an electron source for directing a beam in a predetermined path against the viewing screen, a crossed-field modulation system as defined in claim 1 having two coaxially adjacent electrode groups arranged sequentially in quadrature and each including four poles, said poles having active faces shaped as rectilinear hyperbolae, with the biasing potentials applied thereto by said first portion of said circuit means being selected to provide a composite crossed-field exerting positive focusing action, and with the first electrode group in the sequence receiving the modulating signal along a focal plane for which the second electrode groups is divergent.
4. In a cathode-ray tube including a viewing screen, and an electron source for directing a beam in a predetermined path against the viewing screen, a crossed-field

modulation system as defined in claim 1 with one of said poles in the electrode group positioned nearest to said beam intercepting anode having a portion closely spaced from the surface on said interceptor anode impinged by the deflected beam, and with the potential applied to said closely spaced pole-portion by said circuit means being more positive than the potential of said interceptor anode, whereby electrons which are scattered from said interceptor anode are separately collected by said pole-portion.

5. In a cathode-ray tube including a viewing screen, and an electron source for directing a beam in a predetermined path against the viewing screen, a crossed-field modulation system as defined in claim 1 and further including a collector anode interposed between said beam intercepting anode and the electrode group positioned nearest thereto, said collector anode having a portion closely spaced from a surface on said beam intercepting anode impinged by the deflected beam, and with said circuit means having a portion for biasing said collector anode positively with respect to said beam intercepting anode for separately collecting electrons which are scattered therefrom.

6. In a cathode-ray tube having a collimator and a cathode for emitting a high current beam of electrons in a predetermined path, a focusing modulator including in combination, an interceptor anode having a spot defining aperture therein of a diameter smaller than the diameter of the beam emitted by said cathode, a multiple electrode structure positioned between the cathode and said interceptor anode, said electrode structure including a least three closely spaced electrode groups each including a pair of semi-cylindrical electrostatic pole-pieces defining a common cavity for passage of the beam, a collector anode between said interceptor anode and the electrode group at the beam exit end of said cavity, said collector anode having an aperture aligned with said image defining aperture and larger than said image defining aperture, circuit means for applying different predetermined biasing potentials to said pole-pieces thereby establishing in said cavity a focusing field having a non-linear spatial potential distribution exerting strong focusing action for converging said beam at the position of said interceptor anode, said circuit means having a portion for applying a modulating signal to half of said pole-pieces for superimposing a transverse field on said focusing field providing a composite field of variable transverse asymmetry, with such composite field being effective to deflect the beam between one extreme condition in which the beam is directed against said interceptor anode and another extreme condition in which the beam is directed through said aperture therein, thereby providing deflection intensity control, and said circuit means having a further portion for biasing said collector anode positively with respect to said interceptor anode for drawing scattered electrons back from said interceptor anode to said collector anode.

7. In a cathode-ray tube, a focusing modulator as defined in claim 6 and further including an apertured pre-focusing anode between the collimator and the electrode group at the beam entrance end of said cavity, and said circuit means applying a positive potential to said pre-focuser anode for preconverging the beam before entry into said cavity.

8. In a cathode-ray tube, a focusing modulator as defined in claim 6 with said circuit means including a variable control for adjusting the biasing potentials applied to said pole-pieces, said control being adjustable to invert the sense of modulation for converting between a positive and a negative picture.

9. A focusing modulator for use in a cathode-ray tube having a collimator and a cathode for emitting a high current beam of electrons in a predetermined path, said modulator including in combination, a prefocuser anode adjacent the collimator and having an aperture therein aligned with the predetermined beam path, a multiple electrode structure adjacent the exit side of said prefocuser anode and including two groups of electrostatic pole-

pieces arranged in sequence and defining a common cavity aligned with the predetermined beam path, each of said groups comprising four pole-pieces arranged in opposed pairs about the predetermined beam path and having active faces shaped as rectilinear hyperbolae bounding said cavity, a collector anode at the exit end of said cavity and having an aperture aligned with the predetermined beam path, an interceptor anode closely spaced from the exit side of said collector anode and having a spot defining aperture therein of a diameter smaller than that of the beam emitted by said cathode and larger than that of said aperture in said collector anode, said spot defining aperture being aligned with the predetermined beam path, and circuit means having a first portion for applying predetermined biasing potentials to said pole-pieces with said opposite pole-pairs in each of said groups being of opposite polarity, one of said groups being rotated 90° with respect to the other for providing a composite crossed electric field in said cavity for focusing the beam at the position of said interceptor anode, and said circuit means having a second portion for applying a modulating signal to one of said pole-pieces in said first group for superimposing a deflecting field on said composite field effective to deflect the beam between one extreme condition in which the beam is directed substantially entirely against said interceptor anode and another extreme condition in which the beam is directed through said spot defining aperture, thereby providing deflection intensity control.

10. In a cathode-ray tube, the combination including, a large area cathode for emitting a high current beam in a predetermined path, an interceptor anode spaced from said cathode and having a spot defining aperture smaller than the diameter of the beam emitted by said cathode, focuser means between said interceptor anode and said cathode for focusing said high current beam into a crossover at said spot defining aperture, said focuser means including a multiple electrode structure providing a composite focusing field having a variable transverse component for deflecting the entire focused beam in one lateral direction substantially entirely out of said aperture and onto said interceptor anode about said aperture, means for providing modulation potential at said electrode structure effective to vary the deflection of the beam with respect to said spot defining aperture and said interceptor anode about said aperture so that the total beam current supplied to said interceptor anode and said aperture therein is substantially constant and the portion of the beam current which passes through said aperture varies from a cut-off value to a maximum value, an image forming lens spaced from the beam exit side of said interceptor anode, and concave post-focusing means at the exit side of said spot defining aperture for concentrating the beam before it enters said image forming lens.

11. In a cathode ray tube, the combination including, a large area cathode for emitting electrons in a predetermined path, an interceptor anode spaced from said cathode and having a spot defining aperture therein, electrode means positioned between said interceptor anode and said cathode, said electrode means including a plurality of poles providing a composite electric field having both axial and lateral components in the path of the electrons, said poles of said electrode means being positioned so that said field is effective to focus electrons from said cathode into a crossover at said spot defining aperture and to deflect substantially all of such electrons laterally away from said spot defining aperture and onto said interceptor anode about said aperture, and means for applying modulation potential to said electrode means to vary the deflection of the electrons with respect to said spot defining aperture to thereby control the portion of the electrons which passes through said aperture, said large area cathode providing substantially constant electron current to said interceptor anode and through said aperture therein, with the portion of the electron current passing through

said aperture varying from a cut-off value to a maximum value.
